VENTILATED CAP

Milton S. Kaye, Newton, and Arnold J. Kaplan, Quincy, Mass. (both of 116 Bedford St., Boston, Mass.)

Filed Dec. 6, 1963, Ser. No. 328,536

6 Claims. (Cl. 2—209.4)

The present invention relates generally to hats and more particularly to those generally classified as caps, especially uniform caps of the type worn by policemen, firemen, conductors and others.

In the manufacture of caps and particularly uniform caps having peaks, it has been the practice heretofore to shape the crown and basal portion of the hat with the aid of frames which have heretofore been formed of cane material. Originally this cane material was made of a closely woven material with individual vertical strands extending substantially beyond the uppermost parallel strand. Later a similar construction was utilized wherein woven material was formed of an open cane so as to provide greater ventilation. In all of these earlier modifications the individual vertically oriented cane strips were flared outwardly and individually secured to reinforcing elements for purposes of shaping the cap and particularly the crown portion. This frame material formed of cane strips is relatively heavy, bulky and difficult to handle. Moreover, cane material splinters, is subject to cracking if flexed to too great an extent and is not easy to stitch. The individual elements are likely to split if perforated by stitching. Moreover, the vertically oriented cane strips do not normally align with one another properly and have to be treated individually, often with great difficulty and expense. In the case of the open mesh cane strip frame used in ventilated caps, little protection was afforded against rain. In addition, these cane frames have qualities which otherwise inherently limit the ability to style caps, particularly ventilated caps in which they are used. In addition, such cane frames are relatively expensive and easy to permanently damage.

It is an object of the present invention to provide a uniform cap construction particularly for uniform caps having peaks wherein the cap is provided with an improved foundation construction formed of a self supporting woven material of relatively fine strands forming a rigid interlock porous mesh which is unusually light in weight and is particularly suited for use in ventilated cap constructions.

A further object of the present invention is to provide a uniform cap construction having a frame which is formed of an inexpensive woven material that is relatively easy to handle in manufacture, is rigid and resilient, is capable of withstanding substantial strains and stresses and will retain its form even after being subjected to deforming pressures for long periods of time.

A further object of the present invention is to provide a uniform cap construction which is particularly suited for ventilated cap constructions and in which the frame of the cap is not only relatively rigid and resilient but is also very light and sufficiently porous to readily pass circulating air.

A further object of the present invention is to provide a frame for a uniform cap which frame is formed of woven material having a plurality of interwoven parallel horizontal strands and vertical strands, with the uppermost group of parallel strands severed at regular intervals about the frame whereby the upper portion of the frame is divided into a plurality of upwardly extending tabs. These tabs, each of a porous woven mesh, may be flared outwardly to support the crown of the uniform cap in a rigid permanent shape.

A still further object of the present invention is to pro-

2

vide a uniform cap frame formed of flexible woven material which is self supporting, with the flexible material rolled into a substantially circular form, with the upper portions of the circular form or frame cut vertically at regular intervals to divide the upper portion into upwardly extending tabs with each tab itself formed of woven material. The upwardly extending tabs are flexed into selected shapes and secured in these shapes by reinforcing means in the form of reinforcing tapes and bindings which prevent sagging, warping and distortion of the cap and thereby assure maximum wearing qualities in a lightweight cap.

A further object of the present invention is to provide a cap construction which embodies a frame of lightweight construction formed of woven material with the frame having lower and upper portions both of woven material.

A further object of the present invention is to provide an improved uniform cap construction having a woven frame of the type described, which is particularly useful and adapted for shaping in manufacture and which may be made economically and with greater uniformity than caps of the type heretofore made.

It is a further object of this invention to provide a construction which not only affords a means in which uniform caps may be ventilated but in which such uniform caps are also resistant to the passage of rain and water through the ventilated portions of the caps.

These and other objects and advantages of the present invention will be more clearly understood when considered in conjunction with the accompanying drawings in which:

FIG. 1 is a side elevation view showing one form of the improved cap construction of this invention;

FIG. 2 is a fragmentary cross sectional elevation taken substantially along the line 2—2 of FIG. 1;

FIG. 3 is a side elevational view of another form of the improved cap construction of this invention with a portion of the cap body broken away to show the details of construction;

FIG. 4 is a plan elevation of the material of which the frame is formed, and

FIG. 5 is a fragmentary cross sectional elevation similar to that of FIG. 2 but of a further modification of the invention.

Referring to FIGS. 1 and 2 there is illustrated a preferred form of this invention wherein ventilation is provided in the basal portion 1 as well as the crown portion 2 of the uniform cap. In this arrangement, a frame 3 is formed of a woven mesh material best illustrated in FIG. 4. This woven mesh material is formed of a plurality of parallel horizontal strands 5 interwoven with a plurality of parallel vertical strands 6.

The strands 5 and 6 may be formed of any suitable material which is capable of being woven into a self supporting web and in which the web is flexible, noncorrosive, and is dimensionally stable. While various plastic materials may be used, nylon has been found the most satisfactory and preferred. The strands are preferably monofilaments of nylon or the like which are locked into their woven position by suitable adhesive. Other materials may also be used provided they afford sufficient rigidity. If desired, the material may be sized to add stiffness to the web of which the frame 3 is formed. The web illustrated in FIG. 4 may be formed by preparing elongated strips of uniformly woven material and then cutting one side edge 8 with a series of parallel slits 9 extending inwardly from the side edge 8 for a distance which preferably approximates half of the width of the strip but may vary depending upon the particular application for which the frame is being prepared. The web is cut to a length sufficient to form a circle having a diam-

eter related to the size of the hat for which the frame is being prepared. The frame is circularly formed with a portion of the cut ends overlapping. The lower edge 12 of the frame 3 has a reinforcing strip 14 secured to it. This reinforcing strip which extends all the way around the hat may be formed of cardboard or similar material. A finish binding 15 is positioned with one portion 16 on the inside and the other portion 17 on the outside of the frame 3. The inside portion 16 of the finish binding 15, the reinforcing strip 14, the frame 3, the outside portion 17 of the finish binding and an outer covering 23 may be stitched together by stitching 13. The sweat band 18 is stitched to the finish binding by stitching 19. The sweat band 18 may be formed of any suitable material such, for example, as leather or synthetic leather. The finish binding 15 is preferably formed of a twilled cloth.

In the ventilated hat construction illustrated in FIG. 2 the basal portion 1 is preferably provided with an outer cover 23 which may be formed of a heavy decorative open meshed cotton or other fiber. The openings formed in the outer covering 23 are preferably larger than those formed by the frame 3. Preferably the frame 3 is formed of a mesh material having openings in the order of 400 openings per square inch. This has been found effective in such constructions to effectively prevent the passage of water, under normal conditions, through the ventilated portions of the hat.

The frame is provided with a reinforcing tape 28 which extends all the way around the frame on its inner side preferably on a level below the tabs 29 which are defined by the slits 9 in the web 3, and preferably below the upper edge 30 of the basal band. This reinforcing tape 28 may be formed of any relatively stiff self supporting material such as cloth covered wire which may be stitched to the frame. The tape 28 is stitched to the frame 3 by stitches 35.

The upper edge of the frame 3 is provided with a series of tabs 29 defined each from the adjacent ones by downwardly extending slits 9. In the preferred embodiment which is utilized in connection with a ventilated cap having an outwardly flared crown 2, the tabs are flared outwardly. However, it is possible to use the present construction in caps wherein the crown is not outwardly flared. The upper edges 8 of the frame are secured in fixed relation by an inverted U-shaped felt padding 36 which extends all around the frame. This padding 36 is in turn covered and secured by a finish binding 37 with the finish binding 37 stitched to the frame 3 through the felt 36 by means of stitches 38. The stitches 38 may also secure, if desired, the frame 3 at its upper edge, felting 36, and binding 37 to the outer side wall 39 of the crown and the top 40 of the hat. In this arrangement, the top 40 is formed of any suitable material, preferably leather or a waterproofed material, and has its periphery folded over the upper edge of the wall 39 as indicated at 41.

The hat may be suitably finished with a visor 42 secured between the sweatband and frame by suitable well known means and may also be provided with decorative bands of the type illustrated at 44.

In the construction illustrated in FIGS. 1 and 2 the outer covering 23 and outer wall 39 are both open mesh construction formed, for example, of open woven cotton, nylon or other material. These open mesh coverings preferably have openings larger than those in the frame 3 and freely pass air therethrough. The frame 3, however, while also passing air is provided with a mesh sufficiently small so as to effectively occlude the passage of

any water that may pass through the outer covering of the hat.

The tabs 29 are readily stitched to the binding 37 and as well as the outer wall 39 and the top 40, since each tab is provided with a weblike portion which is readily adapted for engagement with the stitches 38.

In the embodiment illustrated in FIG. 3 like figures refer to like portions of the preferred embodiment of FIG. 1. In this arrangement, however, the outer covering 23A is formed of a closely woven relatively nonporous material which will not ventilate the lower portion of the cap instead of the open mesh illustrated at 23 in FIG. 1. The crown portion of the cap is, however, formed in a manner similar to that illustrated in FIG. 1 and ventilation is provided in the crown portion.

Another form of the invention is illustrated in FIG. 5 wherein like numerals refer to like portions of the preferred embodiment of FIG. 1. In this arrangement, however, the cap is a nonventilated style commonly used during the winter. Here, the felt padding 36 extends downwardly the height of the crown 2' and the height of the basal portion 1' and is secured between the frame 3 and the finish binding 15. The outer side wall of the crown is formed in a closely woven material 39' which is not adapted to pass air for ventilation purposes. Similarly the outer covering 23' of the basal band 1' is a closely woven material or nonporous fabric that is not adapted to pass air or moisture.

What is claimed is:

1. In a cap construction a circular frame formed of self supporting woven material with said material having a plurality of parallel horizontal strands extending around said frame and a plurality of parallel vertical strands interwoven with said horizontal strands, and with the uppermost of a plurality of said horizontal strands severed along a plurality of vertical lines at regular intervals about said frame to form the upper portion of said frame into a plurality of upwardly extending spaced tabs with each tab formed of said uppermost plurality of discontinuous horizontal strands interconnecting a plurality of vertical strands.

2. A construction as set forth in claim 1 wherein said tabs are flared outwardly and are secured at their ends to a continuous means which secures said tabs in fixed relation to one another.

3. A construction as set forth in claim 2 wherein said frame has a continuous reinforcing tape secured to it above the bottom edge of said frame and below said tabs.

4. A construction as set forth in claim 1 wherein said cap construction is formed with an outer cover overlying said mesh with said outer covering having a plurality of mesh-like openings of greater size than the openings formed by said strands of said frame.

5. A construction as set forth in claim 1 wherein said frame is formed of woven monofilament nylon.

6. A construction as set forth in claim 5 wherein said tabs form mesh-like members stitched to portions of a hat crown.
